UNITED STATES PATENT OFFICE.

WILLIAM L. LINDSLEY, OF SWISSVALE, PENNSYLVANIA.

PORCH-SWING.

1,121,027.

Specification of Letters Patent. Patented Dec. 15, 1914.

Application filed August 9, 1913. Serial No. 783,876.

To all whom it may concern:

Be it known that I, WILLIAM L. LINDSLEY, a resident of Swissvale, in the county of Allegheny and State of Pennsylvania, have invented a new and useful Improvement in Porch-Swings, of which the following is a specification.

This invention relates to swings and swinging seats, and more particularly to swinging seats ordinarily designated as porch swings.

The object of the invention is to provide a device of this character which can be readily moved from place to place, which is not confined to a single location such as ordinary porch swings suspended from the ceiling, which is slight and neat in appearance, and which has all of the comforts of ordinary porch swings.

The invention comprises the construction and arrangement of parts hereinafter described and claimed.

In the accompanying drawings Figure 1 is a front elevation of a porch swing embodying the improvements; Fig. 2 is an end elevation of the same; Fig. 3 is a plan view showing only one end of the swing; Fig. 4 is a detail sectional view showing the clamp; and Fig. 5 is an enlarged view of the detachable link.

Ordinarily, porch swings are suspended from hooks or rings secured in or to the ceiling of the porch and therefore are not readily movable to suit conditions of weather or exposure, and generally are not usable indoors during the winter time.

The principal object of this invention is to provide a porch swing or other similar swinging seat or couch, which can be readily moved about to suit varying conditions of weather or exposure and which can be used indoors and on the lawn with equal facility.

In the drawings 1 represents the swinging seat or couch, being shown in the typical form of one style of porch swing now quite extensively used. It will be understood, however, that any other design, construction or size of swinging seat may be substituted for that illustrated, the particular construction and design of this seat not being an essential of the invention. Instead of supporting this swing from the ceiling it is suspended from a suitable movable support of such resiliency that in action it gives all of the movements of ordinary porch swings. As illustrated this support is formed of a

base portion 2 and uprights 3, the upper ends of which are preferably bent or curved inwardly to form cantaliver arms 4 from which the swinging seat is supported by suitable elastic members, shown as the springs 5. As illustrated, the uprights 3 and cantaliver arms 4 are formed of resilient spring steel, and preferably the base members 2 likewise will be formed of such steel. At 60

each end there will be at least two uprights 3 with cantaliver arms 4 thereon, and also two spring members 5, one for each corner of the swing, and for large sized swings which are likely to be heavily loaded at 65

times, a central or third upright with cantaliver arm and spring member is preferably employed. The drawings show the construction for large sized swings with the central upright and cantaliver arms. The base 70 member 2 will have as many bars as there are uprights and cantaliver arms, the drawings showing the two side bars and a central bar. As illustrated, the two side bars 75

2^a are spaced a considerable distance apart 80 in order to form a stable base, and the central bar 2^b is midway between the two. These bars are secured to suitable cross members 6, the attachment being made by any suitable means, such for instance as clips 7, 85

and the end cross members 6 are preferably provided with casters or small wheels 8 upon which the swing can be readily moved about. The ends of the base members 2^a and 2^b are turned upwardly to form the inclined end 90

portions 2^c, and have their ends brought into line with the uprights 3. The uprights 3 might be integral with the base members 2^a and 2^b, but preferably are detachable therefrom in order that the swing can be 95 more easily shipped in knock-down condition. To this end the lower ends of the upright members 3 are suitably secured to a

transverse connecting member or clamp 9 which preferably is in the form of a forging 100 to which the members 3 are secured by welding or other means giving a strong, permanent connection, said forgings 9 being provided in their lower edges with vertically arranged openings for receiving the upper 105 ends of the base members 2^a and 2^b, which are secured therein by suitable means providing for ready detachment, such as set screws 11.

The uprights 3 extend upwardly from the 110 forging 9 in parallel planes, and when three are used as shown in the drawing, the cen-

tral one is substantially midway of the two side ones. The cantaliver arms 4 on these uprights are preferably formed on gradual curves, as shown, forming in effect goose necks, although this is not absolutely necessary. The front and rear cantaliver arms are inclined away from each other, as indicated in Figs. 2 and 3 so that the elastic suspending members 5 which connect these front and rear cantaliver arms with the corners of the swing pull substantially in a straight line, as shown in Fig. 2. The elastic suspending members are preferably strong helical springs, as illustrated, all the springs being of the same length. The upper ends of these springs are provided with eyes 12 which are secured to the ends of the cantaliver arms by means of detachable links 13, sometimes spoken of as split links, which connect the ends of the springs to the ends of the cantaliver arms, but which permit of ready detachment. The lower ends of the springs are likewise provided with eyes 14 which are secured to the upper ends of eye-bolts 15 which extend down through the corner posts of the swing and are provided at the lower ends with ornamental nuts 16. When a central suspending member is used the swing will be provided with a central post 19 through which the connecting eye-bolt will pass. This manner of attaching the springs to the swing is, however, merely illustrative, as obviously any other suitable connection between the swing and the springs will answer the purpose equally as well.

The uprights 3 and cantaliver arms 4, as well as the base members 2^a and 2^b are formed of bars of spring steel of such cross sectional size as to give a perfectly secure support, but one which will, nevertheless, yield under the action of the spring. When the swing moves backwardly the helical springs 5 and the cantaliver arms 4 connected to the rear corners of the swing will yield, the cantaliver arms moving downwardly, the uprights bending slightly inwardly and the springs extending. When the swing moves forwardly the springs and cantaliver arms and uprights supporting the forward corners of the swing yield in the manner described, while those connected to the rear corners of the swing resume their normal positions to a greater or less degree. As a consequence the swing has a substantially parallel motion as though it was sup-

ported by parallel links, as is the case with ordinary porch swings. It has just as free a swinging movement and if anything is much more resilient than ordinary porch swings. It therefore provides all of the comforts of ordinary porch swings and at the same time is so constructed that it can be readily moved about from place to place, such as with changes of sun during the day 60 or on account of exposure to wind or weather, and can be moved indoors in the winter time and used with the same facility as on the porch. The swing, therefore, is adapted for use during the entire year, instead of merely in the summer time, and its use is not dependent upon the condition of wind or exposure to the sun or other elements, as it can be readily moved to a suitable location. 75

The swing can also be used on the lawn or upon terraces or porches having no roof, and to this end may have a suitable canopy support, such as indicated by the uprights 20 secured to the body of the swing or seat. 80

It will be readily understood that the character and design of the body of the swing itself and the specific means for attaching the swing to the yielding suspending members may be varied within wide 85 limits without departing from the spirit of the invention.

What I claim is:

In a device of the character described, the combination of a swinging seat, a movable support therefor comprising a base having at one end a plurality of upwardly extending members, an upper member at each end of said base comprising a connecting member having sockets opening downwardly to 90 detachably receive the free upper ends of the upwardly extending members at its end of the seat and having a plurality of uprights in one piece therewith, clamping means carried by said connecting member 95 and arranged to engage the ends of said upwardly extending members, the upper ends of said uprights being curved inwardly toward the ends of said seats, and a suspending member connecting the ends of each of 100 said inwardly curved portions to the seat. 105

In testimony whereof, I have hereunto set my hand.

WILLIAM L. LINDSLEY.
